TYPEWRITING MACHINE

Jesse A. B. Smith, Stamford, Conn., assignor to
 Underwood Elliott Fisher Company, New York,
 N. Y., a corporation of Delaware

Application October 15, 1935, Serial No. 45,067

14 Claims. (Cl. 197—126)

This invention relates to typewriting manifolding.

Much time has been lost in the handling of individual letter sheets. This invention utilizes a roll of continuous carbon paper, single or multiple, in combination with a carbon holder, which guides the work-sheets to the platen. The carbon sheets remain in position during successive typing operations.

10 The duplicating strips are retained in position so that succeeding groups of work-sheets can be assembled in proper relation to the duplicating strips, with a minimum of handling; the retaining means permitting the worn out portions of 15 the carbon sheets to be withdrawn.

Another object is to provide improved means for quickly and positively aligning the work-sheets in proper relation to the duplicating strips.

20 A further object is to provide means whereby a copy of an envelope address can readily be made on the office or "file" copy, to prove the accuracy of the envelope address.

According to the present improvements, a supply spool of carbon web, of the desired number 25 of plies, is mounted upon a rear extension of the carriage of the typewriter. Upon a flexible work-carrier is provided a cross-band, and the end portions of the carbons are threaded under said band, whereby they are loosely clipped to the work-carrier. The carrier is then inserted, together 30 with the carbon plies, at the rear of the platen, and the platen is rolled to bring the carrier and carbon up in front of the platen; the carbon paying off from the supply spool at this inserting 35 operation. The leading portion of the carrier is laid upon an intercalating table, which extends upwardly and rearwardly from the delivery side of the platen. The band retains the carbon plies, 40 whose leading ends are then clipped forwardly, so that a work-sheet may be laid upon the leading portion of the carrier. The work-sheet is set down to a gage. The gage consists of two stops, one at each side of the carbon-path, to permit the relatively narrow carbons to advance past the 45 stops. Then the lowest carbon-ply is laid back upon the work-sheet. Then a second sheet is laid upon said lowest carbon-ply. Then the second carbon is laid over upon the second work- 50 sheet, and so on. The intercalated sheets, with the carrier, are then rolled backwardly into the machine, to bring them to position to receive the first line of typing.

After typing the page, the assemblage is advanced far enough for the work-sheets to clear the bottom rolls (the top rolls having been cast

off), and then the work-sheets are withdrawn from the machine. Fresh sheets are inserted as before. When the carbon is worn, the carrier is temporarily clamped to the work-table, while the carbon-plies are pulled forwardly and the 5 worn portion is torn off by a knife.

An envelope to accompany the typed letter, may be inserted with its bottom resting upon the side stops below the top edge of the band or clip, and a small carbon-sheet may be placed between 10 the envelope and the original work-sheet, and the address that is typed upon the envelope will be duplicated upon the work sheet or sheets.

Other features and advantages will hereinafter 15 appear.

In the accompanying drawings, Figure 1 is an end view, partially in section, of the manifolding attachment as applied to an Underwood standard typewriter.

Figure 2 is a perspective of the guide or holder 20 for the duplicating strips and work-sheets.

Figure 3 is a sectional view of the work holder taken through A—A of Figure 2, showing two 25 duplicating strips in position.

Figure 4 is a perspective of the invention. 25

Figure 5 is a sectional end view of the knife in cutting position.

Figure 6 is a perspective illustrating the method of removing the used carbon strips preparatory to cutting them, with portions of the strips torn 30 away to illustrate details of the invention.

Figure 7 is an end view showing how the slack of the duplicating strip roll might tend to loop around the roller as the work-sheets are brought 35 into typing position.

Figure 8 illustrates a weighted roller to overcome the condition illustrated by Figure 7.

Figure 9 is a perspective of a removable work 40 rack or support.

Figure 10 is an end view showing the weighted roll in position and the work-rack in use.

Figure 11 is a perspective illustrating an addressed envelope in position in the work holder so that the typewritten address will appear on the duplicate copies of the letter.

Figure 12 represents a copy of a letter on which the envelope address appears.

Referring to Figure 1, a platen 10 is journaled in the end frames 11 of a platen-carriage so as to be revoluble about its axis 12. Suitable knobs 13 fixed to shaft 12 serve as a means to revolve the platen manually. The usual paper-table 14 having a forwardly curving apron 15 is suitably secured to the carriage frame 24. Slots 16 and 17 formed in the apron permit the lower feed-

rolls 18, 19, to engage the work-sheets. A type-bar 20 is shown in printing position.

A flanged end-roll 21 of multiple carbon paper slightly narrower than the work-sheets with 5 which it is to be used is mounted on a shaft 22, and supported between rearwardly and upwardly projecting arms 23 which may be secured to the carriage frame 24 by means of the brackets 25 which support the tabular rack 26. To facilitate the removal of the carbon roll and shaft one arm 23 may be formed with a hole 27 to loosely journal one end of roll shaft 22, while the other arm may have a suitable round bottom slot 28 to cradle a reduced diameter end of 15 the roll shaft. The carbon roll is preferably adjustable laterally on the roll shaft, in which case means such as the collars 29 and set-screws 30 may be used to fix the roll firmly to the shaft. Lateral movement of the roll shaft relative to the 20 brackets is prevented by forming the end engaging the bracket-slot 28 of suitably smaller diameter than the remainder of the shaft so that a shoulder 31 will engage the inner wall of the bracket. At the opposite end a detent gear 32 25 suitably fixed to the shaft 22 engages the detent spring 33, which serves to prevent the accidental rotation of roll 21, and also urges the shoulder formed in the shaft against the inside wall of the bracket.

30 Intermediate their ends, the arms 23 carry a transverse rod 34 parallel to shaft 22 and secured by means such as a screw 35 at one or both arms. An inverted L-shaped guard 36, having a forwardly projecting horizontal member and a 35 downwardly projecting vertical member, is secured to rod 34 so as to overlie the latter and serve as a guard to prevent the slack carbon paper 37 from encountering the fixed frame 38 of the machine.

40 The carbon paper and work-sheet holder, Figure 2, is composed of a substantially rectangular back-sheet 39 of heavy paper or other durable, flexible material, preferably about two or three inches longer than the work-sheets or stationery 45 19, and slightly wider, except for the lower two or three inches, which increase about one half inch in width on each side. A rectangular front member 40, which may be of stiff cloth, has dimensions approximately equal to the lower portion 50 of the back-sheet, and is fastened thereto by staples 41, as illustrated, or by suitable stitching or adhesive. The inner edges of the fastening should be in parallel relation to each other and to the edges of the holder.

55 The front member 40 is so located as to have its lower edge parallel to, and about $\frac{1}{2}$ " above the lower edge of the back-sheet. The fasteners 41 for securing the front and back members 40, 39 are so placed as to leave the upper half inch 60 of the front member free, forming a flap 42 to facilitate the insertion of the front sheets; with the distance between the inner edges of the fasteners suitable to prevent the passage of the work-sheets, they, therefore, resting on the upper edges of the fastening devices, which, being 65 parallel to the lower edge of the holder, position the work-sheets in rectilinear alignment.

The carbon paper holder 39, 40 is substantially a sleeve, which in use is slipped over the carbon 70 paper, back-sheet uppermost, with the carbon coated side facing the back-sheet. The carbon sheets 43 are drawn through the holder until the leading edges are even with the lower edge of the holder.

75 The holder with the carbons in place, may now

be inserted into the machine from the rear in the usual manner and rolled forward until the upper part of the front unit is about $\frac{1}{2}$ " above the upper feed-rollers.

As the carbon paper holder unit also holds the 5 work-sheets during the typing operation, the holder unit must be free to move as the platen is rotated, but when the carbon sheets are to be replaced, it is desirable to anchor the holder unit 10 to permit the used carbons to be withdrawn therefrom without removing the unit from the machine.

To this end I employ a pair of clamps 44 mounted on a transverse shaft 45 disposed within the curved upper portion 46 of the paper table 15 14, and journaled in rearwardly and upwardly extending brackets 47 secured to a transverse member 48 fixed to the platen frame. The clamps 44 are forwardly and downwardly extending metal tongues with inwardly pointing extremities 49 carrying gripping sleeves 49a of rubber or similar material. The clamps are fixed to the shaft and so located that the gripping extremities can engage the extending sides at the lower portion of the work holder.

A helical spring 50, one end engaging the bracket 47 as at 51 and the other end inserted in a suitable hole 52 in an arm 53 fixed to shaft 45, urges the shaft in a clockwise direction. A manually operable lever 54, the front end of which 30 is formed into a finger-piece, is suitably pivoted intermediate its ends on a projection 55 from bracket 47. The rear end of lever 54 has fixed thereto an inwardly projecting pin 56 to engage suitably curved notches 57, 58, formed in the 35 forward edge of arm 53.

With the lever 54 raised so that pin 56 engages the outer notch 58, the grips 49a will be raised clear of the work-sheets and carbon holder, as 40 shown in Figure 1. When it is desirable to anchor the carbon holder, as when fresh carbon sheets are to be drawn into position, the platen 10 is rotated so as to bring the extended edges of the holder into position between the clamps and the paper-table, and the lever 54 is depressed to 45 throw pin 56 into engagement with the inner notch 57 of arm 53, thus rotating shaft 45 counterclockwise against the tension of helical spring 50 and suitably pressing the grips 49a 50 against the carbon holder to anchor it.

One of the clamps 44, preferably the left-hand one, may carry a suitable upwardly projecting guide 59 at its hub end, to contact the extended edge of the carbon paper holder and act as a side-edge guide. Accidental transverse shifting 55 of the clamp mounting rod 45 is prevented by a suitable collar 60 at the extremity opposite the helical spring.

Each end of the platen frame 11 is formed with a horizontal plane upper surface on which a plate 61 is secured, as by screws. Intermediate its extremities, but toward the rear, plate 61 is formed with a pair of integral, oppositely disposed lugs 62 extending upward, and suitably drilled to receive a continuous shaft. A leaf spring 63 riveted 65 to plate 61 has its free end extending between the lugs.

The upper or auxiliary feed-rollers 64 are mounted on a bar 65 which engages a pair of rearwardly extending arms 66, the extremities of 70 which are outwardly bent to form shafts suitable for journaling in the bearing surfaces formed in the lugs 62.

The shaft extremity of each arm has secured thereto, as by set-screws, an eccentric collar 67 75

- disposed between the lugs 62 of the plate 61 and above the leaf spring 63. It will be understood that the collars are slipped over the shafts as the latter are being inserted into the lug bearings.
- 5 The collars are of sufficient width to permit ready rotation of the feed-roll shaft assembly, but to prevent its excessive lateral shifting. Each collar is shaped to act as a cam which its associated leaf spring engages so as to yieldably retain the 10 feed-roll shaft assembly in either its operative or inoperative position, as determined by the operator.

A knife bar 68 having a rear cutting edge against which to tear the used carbon paper is 15 secured to the upper feed-roll shaft supporting arms with its forward edge close to but suitably clearing the upper feed-rolls.

The rear edge of the assembly, when the latter is being rolled back into writing position, is liable 20 to carry over the top of the carbon roll, looping the slack carbon paper in some such manner as shown by Figure 7. To overcome this condition, I use an idler spool 69, having suitably flanged 25 ends, to ride on the carbon paper between the carbon roll and the carbon holder assembly. The spool may be of wood or other light material, as it weight is used merely to draw the end of the carbon holder assembly downward over the 30 edge of the paper table so as to clear the carbon roll, and to prevent the formation of slack on the carbon roll.

A simple rack is formed by an upwardly and rearwardly extending cross-bar 70 on which are 35 secured metal strips 71, shaped to form a skeleton table surface on which the work-sheets may rest, the front portion of the strips being curved around the platen, with rearwardly extending continuations having curved extremities to act as a guide to preclude the interference of the work-sheets and carbon holder with the carbon paper 40 roll.

For mounting the rack, the upper pressure roller shaft support plate 61 is modified to include an upwardly extending rear bracket 72. A rivet 45 73 having a neck and head 73^a disposed behind the bracket secures a front plate spring 74, which at its upper portion is formed with a suitable recess to engage a ball 75 and urge it into an adjacent hole 76 drilled through the bracket. The 50 hole diameter is slightly smaller than that of the ball, so that a portion of the ball may extend beyond the rear surface of the bracket 72. At its extremities, the table cross-bar 70 is formed with slots 77 of width suitable to engage the neck of the rivets 73 snugly, and holes 78, preferably 55 rectangular, in the rearwardly extending upper portion of the bar, and immediately above the slots. To mount the rack it is necessary only to engage the slots 77 with their associated rivets, 60 after which a downward pressure will seat the slots and bring the holes 78 to a position where the projecting balls 75 will engage the lower end of the holes and serve as a yieldable lock, as 65 illustrated by Figure 9.

65 After the carbon paper holder has been slipped over the carbon sheets and inserted into the machine, as previously explained, the work-sheets 79 may be inserted from the front, and interleaved with the carbons, with their lower edge 70 against the top of the staples or stitching, which acts as a positive aligning means. The original or outer work-sheet is placed behind the extended front flap, and will also be positively aligned by 75 contact with the top of the staples. The assembly is then rolled back into writing position.

After typing, the unit is rolled forward until the upper flap is about $\frac{1}{2}$ " above the wing scales, after which the original and copies of the work-sheets may be removed, leaving the holder 39 in position for the next insertion of work; or the original work-sheet only may be removed, an envelope 80 inserted in its place, and the unit returned to writing position, in which case a carbon impression 81 of the envelope address is made on the manifold copies. Rolling 10 the unit forward again makes it possible to remove the work.

When a fresh supply of carbon is required, the work-sheets having previously been removed, the carbon holder with the carbons is rolled back 15 until the extended lower portion of the holder is beneath the grips 49^a. The grips are brought into operating position by a downward pressure on lever 54 and the usual paper feed-rolls are unlocked. The leading edges of the carbon paper 20 may then be grasped by the operator, as illustrated by Figure 6, and a fresh supply drawn into position.

The used portions of the carbon sheets are torn off against the knife 68, as illustrated by 25 Figure 5, and the holder is again ready for use.

In operation, some of the multiple-ply carbon-web is drawn off from the spool, and the leading end of the web is threaded through the carbon clip or band 40, and drawn up to the top of the 30 backing sheet 39. The latter, with its loosely clipped carbons, is then introduced top-end first downwardly in rear of the platen, and the latter is rolled forwardly until the band or loose clip 40 rises at the front of the platen. Then the 35 upper or leading end portions of the carbon-plies are swung forwardly and laid over the platen. The first work-sheet 79 is then laid upon the leading end portion of the backing sheet 39, and the bottom end of the work-sheet 40 drops to the printing-line gage, which consists of the opposite stops 41 at the upper portion of the carbon-clip. The bottom corners of the work-sheet rest upon these stops; the latter being separated sufficiently to admit the narrow carbon-webs. Thus the position of the work-sheet 45 may pass freely between the stops.

Then the rear or under carbon-leaf is laid back and down upon the said work-sheet. Then 50 a second work-sheet is deposited in the machine, overlying said carbon, and also resting upon said gage 41. Then the second carbon is laid back upon the second work-sheet. Then the third (or original) work-sheet is introduced and 55 laid back upon the second carbon. Thus the work-sheets and carbons are interleaved. The device 71 forms a support against which the combined backing sheet and carbon-clip may rest at such operation.

Then the platen is rolled backwardly, to carry the backing sheet 39 in reverse direction around the platen, together with the band or carbon clip 40, and the carbon-plies and work-sheets, as a unit. Thus the work-sheets are brought to 65 proper position for beginning the first line of typing. The work-sheets are held at their bottom edges by the upper lip of the carbon-clip, and conducted thereby between the platen and the feed-rolls; the latter thereupon serving to 70 hold the intercalated sheets against the platen, Figure 1.

After the typing is completed, the platen is rolled forwardly to bring the work-sheets to releasing or delivery position. For this purpose 75

the clip or band 40 is brought up to its former station at the front of the platen (see Figure 4), and the top rolls 64 are cast off, while the carbons and backing sheet 39 remain in the grip of the bottom rolls 19. At this stage there is no further reason to retain the work-sheets in the machine, and they are grasped by their leading ends and withdrawn, Figure 4. The carbons may again be flipped forwardly over the front of the platen, and fresh work-sheets may be intercalated with the carbons as before.

During the insertion and typing of the sheets, the clamps 49^a may remain cast off. But when the leading portions of the carbons have become worn, the clamps may be swung down against the side tongues 81, to hold the combined backing sheet and carbon-clips, while the operator pulls the multiple-ply carbon-web through the clip, and tears off the used carbon.

From the lower portion of each of the intercalating table-frames 71, there may be extended upwardly and rearwardly a guard 83, overlying the intercalated sheets in their movements to and from the platen, and at their rear ends these guards may arch at 84 over the guide 34, 36, to prevent accidental upward fouling of the pack.

Variations may be resorted to within the scope of the invention, and portions of the improvements may be used without others.

Having thus described my invention, I claim:

1. A manifolding assemblage for a front-strike, revolute platen typewriting machine, including, in combination, a supply of carbon-web arranged behind said platen, and a carbon-web and work-piece holder having a backing sheet, and a transverse band having end attachments to the backing-sheet margins to form a flat sleeve, at the lower portion of the backing sheet, affording an opening through which the carbon-web is threaded, said holder with the inserted carbon-web being run into the machine into position for interleavement of work-pieces with the carbon-web, said sleeve-opening and carbon-web being narrower than said work-pieces, said end attachments of the band forming lower-edge gages to engage the work-piece margins that extend beyond the carbon-web, whereby said work-pieces may be collated by means of said holder.

2. A manifolding assemblage for a front-strike, revolute platen typewriting machine, including, in combination, a supply of carbon-web arranged behind said platen, and a carbon-web and work-piece holder having a backing sheet, and a transverse band having end attachments to the backing-sheet margins to form a flat sleeve, at the lower portion of the backing sheet, affording an opening through which the carbon-web is threaded, said holder with the inserted carbon-web being run into the machine into position for interleavement of work-pieces with the carbon-web, said sleeve-opening and carbon-web being narrower than said work-pieces, said end attachments of the band forming lower-edge gages to engage the work-piece margins that extend beyond the carbon-web, whereby said work-pieces may be collated by means of said holder, said sleeve being of sufficient length so that both the backing sheet and transverse band are confinable between the platen and the bottom feed-rolls when the said carbon-web and work-piece holder is in work-piece-receiving position, whereby the said holder may be drawn smoothly around the platen to bring the interleaved work-pieces and carbon-web into printing position without the loss of alignment thereof, said band

being extended above said attachments, to form a transverse flap for clipping the outermost work-piece.

3. For a front-strike, revolute platen typewriting machine having a rear-insertion paper-table behind the platen, a manifolding assemblage including, in combination, a transfer web, means for paying off said web from a supply behind said platen, and a web-riding work-piece gage and holder, said holder including a flexible back sheet and a substantially shorter flexible front sheet, said back and front sheets having marginal attachments to form a sleeve at the bottom of the holder through which the transfer web is threaded, said attachments also forming bottom-edge gages for work-pieces interleaved with the transfer web, said holder having margins at its lower portion extending beyond said transfer web so as to be engageable by side clamps to clamp the holder against said rear paper-table preparatory to paying off a fresh portion of transfer web.

4. The combination with a typewriter-carriage having end-members, a revolute platen and a rear paper-table, and a carbon-roll supported behind said paper-table, of a sheet-collating support including a cross-bar attached to said end-members in front of said rear paper-table, and a plurality of strips secured transversely to said cross-bar to overlie the top side of said cross-bar to form the collating surface, each strip having a lower end-portion bent reflexly back toward the under side of the bar and beyond the latter to form a guide cooperating with said rear paper-table to guide the incoming carbons.

5. In a typewriting machine comprising a frame, a shiftable carriage-frame, suitable supports to carry a roll of transfer material in fixed relation to said carriage-frame, key-bars and associated type-bars, and a revolute platen to receive a flexible holder through which sheets of said transfer material may pass, said holder additionally serving as a guide for the front insertion of work-sheets, means under control of the operator to engage said holder in such manner as to permit the passage of the transfer material therethrough while preventing the movement of said holder.

6. In a typewriting machine to co-operate with manifolding means including a roll of continuous single or multi-ply transfer sheets and a holder to pass such transfer sheets between its front and rear members and additionally to serve as a guide for the front insertion of work-sheets, locking means which under the control of the operator will engage said holder so as to permit the passage of said transfer sheets therethrough while preventing the movement of said holder, said means comprising a plurality of detent-members mounted on a journaled shaft, means to rotate said shaft so as to bring said detent-members into or out of engagement with said holder, and locking means to retain said detent-members in either an operative or inoperative position.

7. For use with a typewriting machine having a paper-feeding platen, manifolding equipment including the combination of a roll from which a length of transfer web feedable around said platen is paid off to hang in a loop between said roll and platen, said roll being locked after the web is paid off, said loop rising and falling extensively consonantly with advance and return of the paid-off web-portion for typing on sheets successively placed on said platen, and a free idler arranged to hang in said loop and follow

its rise and fall so as to prevent the slackening of said transfer web on said locked transfer-web roll.

8. As an article of manufacture, a holder for transfer sheets and work-sheets for use in manifolding typewritten material, said holder arranged to receive the free end of a transfer web to be introduced therewith around the platen of a typewriting machine, after which introduction the stationery or other work-sheets may be positioned in said holder by front insertion and moved with said holder into typing position; said holder comprising a flexible back sheet, and a substantially shorter flexible front sheet, said front and back sheets being attached together at their margins to form a sleeve through which the transfer web is threaded, the attachments also forming bottom-edge gages for work-pieces interleaved with the transfer web, the width of the holder at its lower portion being substantially greater than the transfer web to form margins, laterally outside of the sleeve, for clamping the holder preparatory to advancing the web therethrough.

25 9. An intercalating device including a backing sheet having a front band, means for supporting the backing sheet for typing, and a carbon-spool mounted on said supporting means, the leading end of the carbon being led over the backing sheet and under the band to be loosely clipped thereby, said sheet having within the side margins of the band opposite stops to gage the bottom ends of the work-sheets intercalated with the carbon-plies.

35 10. An intercalating device including a backing sheet having a front band, means for supporting the backing sheet for typing, and a carbon-spool mounted on said supporting means, the leading end of the carbon being led over the backing sheet and under the band to be loosely clipped thereby, said sheet having within the side margins of the band opposite stops to gage the bottom ends of the work-sheets intercalated with the carbon-plies, the upper edge portion of the band projecting above said stops, to form a lip to guide the insertion of the work-sheets.

45 11. The combination of a typewriting carriage having a platen, an intercalating table extending

rearwardly from the delivery side of the platen, a backing sheet having a front carbon-confining band and side stops within the side margins of the band, and a carbon-spool mounted on said carriage at the rear of the intercalating table.

12. The combination of a typewriting carriage having a platen, an intercalating table extending rearwardly from the delivery side of the platen, a backing sheet having a front carbon-confining band and side stops within the band, and a carbon-spool mounted on said carriage at the rear of the intercalating table, said backing sheet having opposite side extensions, and releasable clamps mounted upon the carriage to engage said extensions to hold the backing sheet while the worn carbon is pulled through the clip.

13. The combination, in a front-strike typewriting machine, of a carriage having a platen and a rear insertion table, an intercalating table extending rearwardly from the delivery side of the platen, a backing sheet having a front carbon-confining band forming a clip and side work-piece-collating stops within the band, a carbon-spool mounted on said carriage at the rear of the intercalating table, said backing sheet having opposite side extensions, releasable clamps mounted upon the carriage to engage said extensions to hold the backing sheet against the rear insertion table while the carbon is pulled through the clip for discarding the worn carbon, and a knife movable to and from an operative position near the delivery side of the platen, for severing the worn portion of the carbon, subsequently to being pulled through the clip.

14. The combination of a typewriter-carriage having a platen, an intercalating table extending upwardly and rearwardly from the delivery side of the platen, a rear paper-table, a backing sheet having a front carbon-confining band and side stops within the margins of the band, to gage the bottom ends of work-sheets intercalated with the carbon-plies, a carbon-spool mounted on said carriage at the rear of the intercalating table, and a guard between the intercalating table and the introductory side of the platen, said guard arching over the rear paper-table for directing the incoming carbons over the latter.

JESSE A. B. SMITH.
